UNITED STATES PATENT OFFICE.

CHARLES HEER, OF PEORIA, ILLINOIS.

DRINKING-FOUNTAIN.

1,085,418.

Specification of Letters Patent.

Patented Jan. 27, 1914.

Application filed January 23, 1913. Serial No. 744,697.

To all whom it may concern:

Be it known that I, CHARLES HEER, a citizen of the United States, residing at Peoria, in the county of Peoria and State of Illinois, 5 have invented new and useful Improvements in Drinking-Fountains, of which the following is a specification.

This invention provides means for supplying poultry and small stock with drinking water both in cold and warm weather, 10 the device being of such construction as to prevent freezing of the water during a cold spell.

The invention provides a fountain for 15 holding drinking water, said fountain embodying a minimum number of parts and a simple construction whereby it may be easily and conveniently replenished and whereby a supply is assured so long as the receptacle 20 contains a surplus amount of water to be automatically fed to the drinking cup as the water is drawn therefrom.

The invention consists of the novel features, details of construction and combination of parts, which hereinafter will be more particularly set forth, illustrated in the accompanying drawing, and pointed out in the appended claims.

Referring to the drawing, forming a part 30 of the specification, Figure 1 is a front view of a drinking fountain embodying the invention. Fig. 2 is a vertical section on the line $x-x$ of Fig. 1.

Corresponding and like parts are referred 35 to in the following description, and indicated in both views of the drawing, by the same reference characters.

The fountain embodies an outer shell or casing 1 within which is arranged a tank 2, 40 a space 3 being formed between the walls of the tank and case for the passage of hot air and gases from a heater 4 which is arranged in the lower portion of the case and consists preferably of a kerosene lamp of ordinary 45 construction. Openings 5 are formed in a side of the case for the ingress of air to support combustion. A large opening 6 is provided in a side of the case opposite the burner to admit of trimming the wick, filling 50 the reservoir with kerosene and to admit of access to the wick raising and lowering mechanism whereby the flame may be regulated. A depression 7 is formed in a side of the case or shell 1, the same increasing 55 in width and depth from top to bottom so as to provide ample room for the stock to

reach the cup containing the water in convenient position for drinking. The tank 2 has a laterally extending portion 8 near its lower end which is open at the top to admit 60 of access being had to the water. A portion of a side of the tank is cut away above the laterally extending part 8 and receives the lower portion of the indented portion 7 of the case or shell 1. The lower end of the 65 indented part 7 extends below the plane of the upper edge of the part 8 so as to dip into the water contained in the part 8 and form a seal. The laterally extending part 8 constitutes a cup from which the stock 70 draws the water in the act of drinking. When the level of the water in the cup 8 lowers to such an extent as to admit air passing into the tank beneath the lower end of the indented part 7 a portion of the water 75 passes from the tank into the cup 8 so as to maintain the predetermined level of the water therein. The indented portion 7 makes ample provision for the stock reaching the water and at the same time provides 80 connecting means between the case 1 and tank 2. The cup 8 projects a short distance beyond the side of the case or shell 1.

It will be understood from the foregoing, taken in connection with the accompanying 85 drawing, that the invention provides a drinking fountain of simple construction and embodying a minimum number of parts and which may be easily and conveniently replenished when required, the cup being 90 at all times supplied so long as the tank contains a sufficient amount of water to form a reserve for replenishing the cup.

From the foregoing description, taken in connection with the accompanying drawing, 95 the advantages of the construction and of the method of operation will be readily apparent to those skilled in the art to which the invention appertains, and while I have described the principle of operation of the 100 invention, together with the device which I now consider to be the best embodiment thereof, I desire to have it understood that the device shown is merely illustrative, and that such changes may be made when 105 desired as are within the scope of the claims appended hereto.

Having thus described the invention what is claimed as new, is:—

1. A drinking fountain comprising a case 110 or outer shell having an opening in a side and having a portion above the opening in-

dented, and a tank having a laterally extending part at its lower end to form a cup, said lateral extension being open at its top and projecting through the opening in the 5 side of the case and having the lower end of the indented portion of the case dipping therein.

2. A drinking fountain comprising a case or outer shell having an opening in a side 10 and having a portion above the opening indented to form a recess which widens and deepens from top to bottom, a heater located within the lower portion of the case, and a tank arranged within the case and

spaced therefrom, said tank having a lateral 15 extension at its lower end which is open at its top, said lateral extension forming a cup which projects through the opening in the side of the case and receives the lower end of the indented part of said case which 20 dips into the water contained therein.

In testimony whereof I affix my signature in presence of two witnesses.

CHARLES HEER.
